UNITED STATES PATENT OFFICE.

WILLIAM H. MECHLIN, OF GREENFIELD, OHIO.

ELEVATOR.

SPECIFICATION forming part of Letters Patent No. 659,406, dated October 9, 1900.

Application filed April 19, 1900. Serial No. 18,541. (No model.)

To all whom it may concern:

Be it known that I, WILLIAM H. MECHLIN, a citizen of the United States, residing at Greenfield, in the county of Highland and State of Ohio, have invented certain new and useful Improvements in Elevators; and I do hereby declare the following to be a full, clear, and exact description of the invention, such as will enable others skilled in the art to which it applies to make and use the same.

This invention relates to elevators, and more particularly to means for automatically opening and closing the hatches or well-doors of hatchways or elevator-shafts as the hoist or car approaches and leaves the hatchway or landing.

The danger of leaving hatchways uncovered, as is often done in warehouses and the like, is well understood on account not only of the liability of persons and merchandise falling through the shaft, but also because of the drafts created and the great danger in case of fire; but the inconvenience attending the use of the ordinary hand-operated doors or hatches has necessitated their abandonment.

The objects of my invention are to provide simple and inexpensive mechanism for automatically opening and closing the hatches or well-doors of elevator-shafts as the hoist or elevator-car approaches and leaves the landings, respectively, and which may be easily applied to ordinary hatchways or placed in ordinary shafts with little difficulty, and, further, to provide means for holding the hatches or doors free or clear from both sides of the shaft or the opposite approaches to the hoist or elevator.

The invention will first be hereinafter more particularly described, with reference to the accompanying drawings, which form a part of this specification, and then pointed out in the claims at the end of the description.

In said drawings, in which corresponding parts in the several views are designated by like letters of reference, Figure 1 is a front elevation of a hoistway or elevator-shaft having the hatch or door operating mechanism embodying my invention applied thereto, the doors or hatches being closed and the operating mechanism being in normal position. Fig. 2 is a similar view showing the hatches

or doors lifted from the hatchway or well-door to permit the passage of the hoist or elevator-car. Fig. 3 is an end view of the structure shown in Fig. 1, parts being broken away, and the operation of the hatch-operating mechanism being represented in dotted lines. Fig. 4 is an end view of the structure represented in Fig. 2, parts being broken away; and Fig. 5 is an enlarged view, in vertical cross-section, of a differential drum or pulley, which constitutes a part of the hatch or door operating mechanism.

The letters A A in the drawings denote beams or timbers constituting a suitable framework for the hoistway or elevator-shaft; a, the floor of the shaft or well; a', a landing having the hatchway a², and B B suitable double hatches or doors for closing said hatchway. The letters C C denote the usual guide-beams for the hoist or elevator-car arranged at opposite sides or ends of the shaft, D a hoist or elevator-car, and e the lift-rope therefor, which may pass through suitable notches between the hatches or doors B and over suitable overhead sheaves or pulleys f f, and thence to the hoisting-drum g on the shaft g', the latter being suitably connected with the hoisting mechanism or engine.

Above the landing a' I preferably provide suitable upright guide rods or beams h h at each side of the front entrance or side of the shaft or hatchway and similar uprights or guides h' h' at the opposite or rear entrance or side of the shaft or hatchway, and suitable slides or slide-pieces i i may be slidably secured to each of said uprights or guides by any suitable means, as by bands i' i', at the lower and upper ends of said slides i i, respectively, loosely embracing the said uprights or guides.

The hatches or doors B B may be pivotally connected or hinged to the lower portions or to the lower bands of the slides or slide-pieces i i, as at b b, by means of the arms b b', one of said doors being secured to the slides on the uprights or guides h h at the front side or entrance to the shaft or hatchway and the other to the slides on the uprights or guides h' h' at the opposite or rear side or entrance to the shaft or hatchway. The hatches or doors are thus adapted to be swung open on their said pivotal connections b b and to be carried, with the slides or slide-pieces i i, up

from the hatchway or landing to clear the entrance thereto. The upper portions or the upper bands of the slides i i may be provided with suitable projections or shoulders i^2 i^2 to 5 form abutments or stops to limit the rearward movement or swing of the doors or hatches on their pivots or pivotal connections b b , the said projections or shoulders i^2 i^2 being slightly in advance of the pivots b b , so 10 that the doors or hatches, if unsupported against the said projections or shoulders, will fall of their own weight and normally close the hatchway.

The doors or hatches B B may be opened 15 or operated by means of ropes, wires, or the like, secured to the doors and passing over pulleys or other suitable supports above the hatchway and connected with the operating mechanism. Ropes k k are preferably fastened or secured at opposite ends of the hatch or door at the front side or entrance to the shaft or hatchway, and, similarly, ropes k' k' to the hatch or door at the opposite or rear side of the shaft or entrance to the hatchway, and 20 25 said ropes k k and k' k' may pass over pulleys l l and l' l' or other suitable supports above the hatchway and at the opposite sides of the shaft, respectively, and thence, either directly or over pulleys or supports l^2 l^2 , to a 30 drum M at the side of the shaft, connected to the hatch-operating mechanism. The pulleys l l and l' l' are preferably located at suitable distances above or nearly above the several pivots of the hatches or doors B B, and 35 said pulleys may conveniently be suspended from the flooring above the hatchway, as may also the pulleys l^2 l^2 , which are located at suitable points or intervals to guide the ropes k k and k' k' about the edges or sides of the shaft to the drum M and to prevent said ropes from passing across the shaft or well, and thus 40 obstructing the passage of the hoist or elevator-car. In order that the ends of the said ropes k k and k' k' which are secured to the 45 hatches or doors may depend vertically from the pulleys l l and l' l' , and thus to keep them out of contact with the elevator or hoist, the said ropes k k and k' k' may be made to pass through suitable apertures in the upper portions 50 of the slides or slide-pieces i i , which may be formed in the aforementioned shoulders or projections i^2 i^2 .

The drum M may be mounted in a hanger n or otherwise supported at one of the sides 55 of the shaft, and the ropes k k and k' k' secured to the drum, so as to wind thereon, and thus open the doors or hatches and draw them up the uprights or guide-beams h h and h' h' on their slides i i when the drum is rotated, 60 the said rotation of the drum being accomplished by drawing upon the rope o , so as to unwind the same from the barrel of the drum. The drum is preferably formed in three parts or sections, as shown in Fig. 5, two of which are 65 of the same diameter and the third of a reduced size, the part m , of smaller diameter, being included between the parts m' m' , of larger di-

ameter and preferably grooved, as at m^2 m^2 , to hold the hatch or door operating ropes k k and k' k' . The rope o , connected to the actuating mechanism, may be secured to the middle part or smaller drum-section m of the drum M, wrapping said section or part a number of times, and the hatch-operating ropes k k secured to one of the parts or drum-sections m' m' , and the ropes k' k' to the other of said parts or sections, so that immediately upon the rotation of the drum M, by drawing upon and unwinding the rope o from the part or smaller drum-section m , the ropes k k and k' k' will wind upon the larger sections or parts m' m' and open and raise the hatches or doors, one pair of the said hatch-operating ropes, as k k , winding over and the other pair winding under the drum, as shown in Figs. 3 and 4. By 85 forming the drum M differentially, as above described, or with the smaller drum-section m for winding the ropes o and the larger drum-sections m' m' for winding the ropes k k and k' k' , the said ropes k k and k' k' will of course travel a greater distance than the rope o , so that by forming the parts m and m' of the drum M of the proper diameters by only a small amount of rotation of the said drum M the hatches or doors may be opened and raised 95 or carried a considerable distance up the uprights or guides h h h' h' out of the way of the sides or entrances to the hatchway.

The actuating mechanism for automatically effecting the rotation of the drum M as the 100 hoist or elevator-car approaches the hatchway may comprise equal bars or levers p p , pivotally attached at or about their middle portions to the outer edge of one of the guide-beams or runners C or other suitable support and 105 pivotally connected or joined at their ends with equal bars or rods p p' , said bars p p and p p' thus forming an adjustable or rocking frame or parallelogram, together with suitable projections, as q and q' , on the hoist or elevator-car for engaging and rocking said parallelogram. The bars p p are preferably 110 pivotally secured to the said guide-beam or runner C at suitable points, one above and the other below the hatchway a' , and at suitable distances from each side of said pivots said bars p p may be inwardly curved or formed with shoulders or projections, as at p^2 p^2 , which will abut the sides of the said guide-beam C when the bars are rocked on their 115 pivots, and thus limit the adjustability of the said bars p p and likewise of the frame or parallelogram.

The rope o , connected to the drum M, may be secured to one side of the frame or parallelogram, preferably to one of the bars p' , as at o' , said rope normally holding the side of the frame or parallelogram to which it is attached uppermost, as shown in Fig. 3, the weight of the hatches or doors B B being sufficient to prevent the drum M from unwinding and letting out the rope o , so that the bars or levers p p may assume the horizontal position represented in dotted lines in Fig. 3.

A tension-spring r may be secured at one end to the frame and at the other end to the guide-beam or runner C to maintain the frame or parallelogram normally in the position described, or any other suitable device may be employed for this purpose.

On the side of the hoist or elevator-car next the frame or parallelogram suitable projections or arms q and q' , hereinbefore referred to, may be provided for engaging the said frame or parallelogram as the car ascends or descends and rocking or adjusting it on its pivotal supports from one to the other of its extreme positions. (Shown more fully in Figs. 3 and 4 in full lines.) One of said projections q (shown in the drawings as a shoulder or ridge on an arm q'' , projecting from one of the uprights d of the hoist) is preferably located at a suitable point or position on the upper part of the hoist or elevator-car to adapt it when the hoist or car ascends to abut or engage and push upwardly the lowermost end of the lower lever p , thereby rocking the frame or parallelogram from the position shown in full lines in Fig. 3 to that shown in Fig. 4, and as the hoist continues to ascend to ride or bear against the vertical rod or bar p' , thus maintaining the said frame or parallelogram in its last-mentioned position till the hoist is clear of the hatchway. The other projection q' is likewise suitably located at the lower part of the hoist or car, at the opposite side of the guide-beam C, to adapt it to accomplish the same result when the hoist descends from above or through the hatchway, the said projection engaging or abutting and pushing downwardly the uppermost end of the upper lever or bar p , thus rocking the frame or parallelogram to the aforementioned position shown in Fig. 4 and as the hoist continues to descend riding or bearing against the opposite vertical bar or rod p' to maintain the parallelogram in said position, as in the former instance, till the hoist or elevator-car has cleared the hatchway.

The operation of the parts hereinbefore described will be apparent. Normally, the hatches or doors being closed, the rope o on the drum M maintains the rocking frame or parallelogram in the position shown in Figs. 1 and 3. As the hoist or elevator-car ascends toward the hatchway its upper arm or projection q pushes against or forces upward the lowermost end of the lower pivoted lever or bar p and the vertical bar or rod p' connected therewith, thus drawing downwardly the opposite or upper end of the said lower lever p , as indicated in dotted lines in Fig. 3, and the opposite vertical bar p' , to which is secured the rope o , and as the rope o is pulled downwardly the drum is caused to rotate and wind the hatch-operating ropes k k and k' k' , thereby opening the doors or hatches. As the drum M continues to rotate and the hatch-operating ropes k k and k' k' wind thereon the doors or hatches B B swing wide

open against the abutments i^2 i^2 on the upper parts of the slides or slide-pieces i i and are then drawn or carried with the said slides, 70 to which they are pivoted or secured, up the uprights or guides h h and h' h' , thus leaving clear both sides of the shaft or entrances to the hatchway, so that access to the elevator-platform is unobstructed. The frame or parallelogram finally assumes the position shown in Figs. 2 and 4, holding the hatches or doors open and clear of or raised from the hatchway, in which position the said frame or parallelogram is maintained till the elevator- 80 car is at a suitable distance above the hatchway by means of the arm or projection q riding or bearing against the uppermost vertical rod or bar p' . (Shown in the drawings to the right-hand side of the guide-beam C.) 85 The lower arm or projection q' will also bear against the opposite or lowermost vertical bar or rod p' , (shown to the left of the said guide-beam C,) and when both arms or projections q and q' have ridden past the upper 90 ends of said bars p p' the weight of the doors or hatches B B (assisted, if desired, by the spring r or other means) will cause them to slide down the uprights or guides h h h' h' to the landing a and drop into place and close 95 the hatchway or shaft, thereby reversely rotating the drum M and rewinding thereon the rope o , which draws the frame or parallelogram back to its formal normal position.

When the hoist or elevator descends or approaches the hatchway from above, the opening of the hatches or doors to permit the passage of the elevator is effected in the same manner as when the hoist is ascending—by means of the lower arm or projection q' on 105 the hoist, which pushes downwardly the uppermost end of the upper lever or bar p till the frame or parallelogram again assumes the position shown in Figs. 2 and 4, and then rides against the lower (or left-hand) vertical 110 bar or rod p' to maintain the frame or parallelogram in said position. The arm or projection q will of course ride against the opposite (or right-hand) bar p' , and when the projections q and q' are past the lower ends 115 of the said vertical bars or rods p p' the doors will again descend and close the hatch, drawing the frame or parallelogram back into normal position.

The apparatus described may of course be 120 applied to the several floors or hatchways of an elevator-shaft, the elevator or hoist operating the hatches successively in the same manner by means of the arms or projections q and q' on the car, which actuate the frame 125 or parallelogram to rotate the drum M. When the doors or hatches B B are closed, they are supported by the pivots b b' and the hatch-operating ropes k k and k' k' , so that access may be had over the shaft or hatchway, or the hatches may be further supported by chains or the like secured to the hatches and to the slides or slide-pieces i i .

It will thus be apparent that my invention

provides a simple and efficient means for automatically actuating the hatches or doors of hatchways or elevator-shafts so as to open and lift the hatches out of the way as the hoist or elevator-car approaches the hatchway or landing and to drop the hatches into position and close them again after the hoist or elevator has passed the hatchway or landing, either ascending or descending, whereby the hatchways or shafts in warehouses or other buildings may be kept covered and the dangers incident to open shafts avoided without the inconvenience attending the use of the ordinary hand-operated doors or hatches or the obstructing of one or more of the sides or entrances to the hatchway and elevator-platform by the open doors or hatches. The apparatus is simple and may be applied with little difficulty or expense to the several hatchways of any ordinary elevator-shaft or hoistway.

It will be understood, of course, that the invention may be susceptible of various modifications and may be applied to automatically operating well-doors of different types than that herein shown. Thus the differential drum M may be dispensed with and others suitable means substituted therefor; but it is preferably employed to adapt the hatches to be lifted a suitable distance above the hatchway with only a small amount of travel of the rope o, which obviates the necessity of making the levers or arms p p of great length.

Having thus described my invention, what I claim as new, and desire to secure by Letters Patent of the United States, is—

1. In combination with the elevator-shaft having suitably-hinged doors for closing the hatchway, mechanism adapted to be actuated by the moving car for opening said doors ascending and descending, comprising a pair of rocking levers with parallel vertical bars or rods pivotally connecting the free ends thereof, flexible connections between one of said rocking levers and said doors for opening the latter when the levers are rocked, so as to permit the car to pass, and means carried by the car for rocking said levers when moving up or down; substantially as described.

2. In combination with the elevator-shaft having suitably-hinged doors for closing the hatchway or opening therein, said doors being adapted to slide vertically when opened, mechanism for opening and simultaneously raising said doors above the hatchway to clear the entrance thereto as the car ascends or descends and for returning the doors to their normal positions and closing them after the passage of the car, mechanism for automatically actuating said door opening and raising mechanism by the passage of the car; substantially as described.

3. In combination with the elevator-shaft having suitably-hinged doors for closing the opening or hatchway therein, said doors being adapted to slide vertically when opened, mechanism for opening and simultaneously

raising said doors above the hatchway to clear the entrance thereto as the car ascends or descends and for returning the doors to their normal positions and closing them after the passage of the car, mechanism for automatically actuating said door opening and raising mechanism comprising a pair of rocking levers having vertically-disposed rising and falling parallel bars or rods pivotally connecting their free ends, and projections carried by the car for rocking said levers and thereby actuating said door-opening mechanism as the car ascends or descends; substantially as described.

4. In combination with the elevator-car having suitable engaging means thereon for engaging door-actuating mechanism at the hatchway as the car ascends or descends, doors for closing the hatchway hinged and slidably arranged within the shaft, means for opening and raising said doors as the car ascends or descends, and mechanism for automatically actuating said door opening and raising means by contact with the engaging means carried by the car whether ascending or descending; said automatically-actuated mechanism being adapted to maintain said doors in a raised position until the car has passed and then to permit their automatic return to and closing of the hatchway; substantially as described.

5. In combination with the car arranged to ascend and descend an elevator-shaft, a pair of centrally-pivoted rocking levers extending transversely of the shaft, one above and the other below the hatchway, vertically-disposed rods or bars pivotally connecting the free ends of said levers, hinged doors covering the hatchway slidably attached to guides upon the shaft, flexible connections between said doors and the parallelogram formed by said levers and vertical bars, for opening and raising the doors when said levers are rocked, and means carried by the car for engaging first the nearest lever and then the adjacent vertical bar as the car ascends or descends, whereby the doors are opened, raised and held in a raised position until the car has passed the landing, and then returned to normal position closing the hatchway; substantially as described.

6. In combination with the car arranged to ascend and descend an elevator-shaft, a pair of centrally-pivoted rocking levers extending transversely of the shaft, one above and the other below the hatchway, vertically-disposed rods or bars pivotally connecting the free ends of said levers, hinged doors covering the hatchway slidably attached to guides upon the shaft, flexible cords or wires connecting said doors over suitable rollers or pulleys with the parallelogram formed by said levers and vertical bars, for opening and raising the doors when said levers are rocked, and means carried by the car for engaging first the nearest lever and then the adjacent vertical bar as the car ascends or descends, whereby the doors are opened, raised and held in a raised

position until the car has passed the landing, and then returned to normal position closing the hatchway; substantially as described.

7. In combination with the elevator-shaft having suitable well-doors, mechanism adapted to be actuated by the moving car for opening said doors when the car is ascending or descending, comprising a pair of rocking levers with parallel vertical bars piv-
otally connecting the free ends thereof, flexible connections between one of said rocking levers and said doors for opening the latter when the levers are rocked, and means carried by the car for rocking said levers when mov-
ing up or down; substantially as described.

8. In combination with the elevator-shaft having suitable well-doors adapted to slide vertically to clear the entrance to the shaft,

mechanism adapted to be actuated by the moving car for raising said doors as the car ascends or descends, and for lowering them after the passage of the car, said mechanism comprising a pair of rocking levers with parallel vertical bars pivotally connecting the free ends thereof, flexible connections be-
tween one of said rocking levers and said doors for raising or lowering the latter when the levers are rocked, and means carried by the car for rocking said levers when moving up or down; substantially as described.

In testimony whereof I affix my signature in presence of two witnesses.
